UNITED STATES PATENT OFFICE.

OBED PECK, OF ROWE, MASSACHUSETTS.

BIT-BRACE.

SPECIFICATION forming part of Letters Patent No. 461,617, dated October 20, 1891.

Application filed January 13, 1891. Serial No. 377,601. (No model.)

To all whom it may concern:

Be it known that I, OBED PECK, of Rowe, in the county of Franklin, State of Massachusetts, have invented certain new and useful Improvements in Bit-Braces, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved bit-brace; Fig. 2, a vertical transverse section of the head or rose; Fig. 3, an end elevation of the chuck; Fig. 4, a vertical longitudinal section of the same, taken between the jaws; Fig. 5, a like view taken through the jaws, and Fig. 6 a sectional view showing a drill-bit in position in the chuck.

Like letters and figures of reference indicate corresponding parts in the different figures of the drawings.

My invention relates especially to an improvement in the chuck and rose of bit-braces; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation.

The chuck B is secured to one end of the sweep by a pin b. The body d of the chuck is reduced at f, and a sleeve g is fitted to rotate on said reduced portion in the ordinary manner. Said sleeve is screw-threaded internally at h. Two flaring spring-jaws i have their inner ends screw-threaded at j and work in the threaded portion of said sleeve, the heads k of said jaws being internally grooved at l and adapted to flare from the mouth of the chuck when projected by the screw in the ordinary manner. The body d of the chuck is provided centrally with an opening m rectangular in cross-section, and the walls of which converge inwardly, the jaws i working on opposite sides of said socket in the usual

manner. This socket is of the ordinary form employed to center a "square-headed" tool.

In my improvement I extend the socket m into the body of the chuck at p, said extension being circular in horizontal section and 55 having its walls converging continuously from the rectangular walls of said socket to a point q at the bottom. By this construction the chuck may be employed for holding a round-shank tool or boring-bit, as C, the head 60 of said bit dropping evenly into said socket, and when clamped by the jaws being firmly centered thereby, as shown in Fig. 6.

The rose D is mounted as follows: The opposite end of the sweep A is cone-shaped at r, 65 to form a step for said rose. An annular groove t is formed in said sweep. The rose-body v is constructed of metal chambered to receive the sweep-end, and provided internally with a seat w for said cone-shaped step. Said 70 body v is provided internally with a chamber 15, with which the groove t in the sweep-end registers. An opening 17 leads through said body into said chamber and a similar opening 18 (see Fig. 1) leads into the sweep-socket 75 above said chamber. A wooden head 16 is secured to said body by means of brads or projections 19, which penetrate said head, and a screw 20, turned into said body and resting in an annular rabbet in said head. The rose is 80 secured in position on the sweep by means of Babbitt metal 21, which is poured into the chamber 15 through the opening 17, and which enters the groove t in said sweep. The duct 85 18 serves to admit oil to the cone bearing, and the Babbitt 21 forms an additional lubricant for the rose while preventing it from being withdrawn from the sweep.

The rose mounted as described, while permitting the sweep to rotate freely prevents 90 all lateral movement and enables the wear to be readily taken up by rabbeting.

The circular or cone-shaped socket forms a bearing for the round shank of the tool C and prevents the same from rocking in the jaws 95 when in use, as frequently happens when such tool is inserted in the ordinary rectangular socket of bit-chucks. Moreover, it is impracticable to extend such rectangular socket to a point at the bottom without forming the 100

chuck-body in sections and at greatly-increased cost, while the cone-shaped socket can be readily drilled by ordinary means.

Having thus explained my invention, what 5 I claim is—

1. A chuck for bit-braces, provided with a tool-socket formed vertically in the body thereof, said socket being rectangular in cross-section at its mouth and having its walls converging continuously inward to a point, the inner portion of said socket being circular in cross-section, substantially as described.

2. In a bit-brace, a chuck provided with screw-actuated flaring jaws and a tool-socket 15 formed in the body of the chuck between said jaws, said socket being angular in cross-section in its outer portion and circular in cross-

section in its inner portion and having its walls converging continuously inward, substantially as and for the purpose set forth. 20

3. In a bit-brace, the sweep A, having the cone-step r and groove t, in combination with the rose D, comprising the body v, chambered at 15, and provided with the seat w, and brads 19, the wooden head 16, the screw 20, turned 25 into said body and projecting into a rabbet in said head, and the Babbitt metal 21 in said chamber, all being arranged to operate substantially as described.

OBED PECK.
